(57) **CLAIM**

The ornamental design for a laser gunsight system for a firearm, as shown and described.

DESCRIPTION

FIG. 1 is a front perspective view of a laser gunsight system for a firearm showing my (our) new design; FIG. 2 is a bottom perspective view thereof;

FIG. 3 is a top view thereof;

FIG. 4 is a right side view thereof;

FIG. 5 is a bottom view thereof;

FIG. 6 is a rear view thereof;

FIG. 7 is a left side view thereof; and,

FIG. 8 is a front view thereof.

The portion of the laser gunsight system for a firearm shown in broken lines forms no part of the claimed design.
